UNITED STATES PATENT OFFICE.

ALICE M. CLARK, OF AMBRIDGE, PENNSYLVANIA.

CURTAIN-POLE.

1,074,164.

Specification of Letters Patent. Patented Sept. 30, 1913.

Application filed May 24, 1912. Serial No. 699,533.

To all whom it may concern:

Be it known that I, ALICE M. CLARK, a citizen of the United States, residing at Ambridge, in the county of Beaver and State 5 of Pennsylvania, have invented certain new and useful Improvements in Curtain-Poles, of which the following is a specification.

This invention relates to improvements in curtain fixtures and has for its object to 10 provide a pivotally mounted curtain pole by means of which the curtain suspended thereon may be swung away from the window whereby ventilation may be readily had and the window conveniently be gotten 15 at to clean.

With the above and other objects in view I have invented the device illustrated in the accompanying drawings in which—

Figure 1 is an elevational view of my improved curtain fixture, Fig. 2 is a top plan view thereof, Fig. 3 is a detail view of a rod section slightly modified, Fig. 4 is a sectional view taken on line A—A of Fig. 2 and Fig. 5 is a view taken on line B—B of 25 Fig. 2.

Like reference characters indicate like parts throughout the specification and in the several views in the drawings in which—

1 and 2 are sections of a curtain pole having spliced removably connected inner ends 3 and 4 and depending right-angular arms 5 and 6. Each of these sections are pivotally mounted in the brackets 7 and 8 which 30 are provided with cylindrical bores in the outer enlarged ends 9 and 10 through which the arms 5 and 6 project and in which they are adapted to rotate.

The abutting spliced inner ends 3 and 4 40 of the pole sections when closed upon one another seat in the recess 11 in the end of the centrally disposed bracket 12. When the pole ends are seated in the recess 11 the extreme end 13 projects slightly above the 45 lower plane of the sections whereby said sections will be held against accidental movements from said bracket 12, as might be the case if one should carelessly handle a curtain hung from the pole, or if a draft 50 were blowing in an open window against said curtain.

In order to swing the sections aside when desired all that will be necessary to do will be to grip one of the knobs 14 or 15 and 55 very slightly raise the arm in order to lift

the ends 3 or 4 from the recess 11, and then turn the knob until the section of the pole swings to the desired position as indicated in dotted lines in Fig. 2.

In Fig. 3 a slight modification is shown 60 in which the end 16 is telescopically mounted on the section of pole 17 whereby the sections may be readily adjusted to various sized window casings. Mounted on the outer ends of each section is a knob 18 and 65 19 held to the section by tubular connections 20 and 21 having cut-away portions 22 to seat over the bracket ends 8 and 9.

Various modifications may be made in the construction and arrangement of the 70 device without departing from the spirit of the invention.

That which I claim to be new and desire to procure by Letters Patent is:—

1. A curtain fixture consisting of pole 75 sections, each having one right-angularly bent end, brackets in which said ends are pivotally seated, said ends extending downwardly to form arms by means of which said sections may be rotated, knobs mounted 80 on said bent portions to form outer ends for said sections, and the inner ends of said sections having over-lapping parts to form a continuous pole, a recessed bracket adapted to receive said overlapping portions and 85 hold said sections against accidental movement.

2. A curtain fixture consisting of pole 90 sections, each having one right-angularly bent end, brackets in which said ends are pivotally seated, said ends extending downwardly to form arms by means of which said sections may be rotated, knobs mounted 95 on said bent portions to form outer ends for said sections, and the inner ends of said sections having over-lapping parts to form a continuous pole, a recessed bracket adapted to receive said overlapping portions and hold said sections against accidental movement, said sections being loosely mounted 100 in said first-named brackets so as to have vertical movement whereby said sections may be raised to be seated in or unseated from said recessed bracket.

In testimony whereof I affix my signature 105 in presence of two witnesses.

ALICE M. CLARK.
